(57) **CLAIM**

The ornamental design for a trash receptacle, as shown and described.

DESCRIPTION

FIG. 1 is a top front perspective view of a trash receptacle shown with a door in a closed position;

FIG. 2 is a front view thereof;

FIG. 3 is a left side view thereof;

FIG. 4 is a right side thereof;

FIG. 5 is a back side view thereof;

FIG. 6 is a top perspective view thereof, shown with the door in the open position;

FIG. 7 is a top view of FIGS. 1 through 5; and,

FIG. 8 is a bottom view of FIGS. 1 through 5.

All features illustrated in phantom line are expressly disclaimed and form no part of the claimed design.

1 Claim, 7 Drawing Sheets
